(57) **CLAIM**

We claim the ornamental design for an automatic tablet packing machine, as shown and described.

DESCRIPTION

FIG. 1 is a top perspective view of an automatic tablet packing machine of the present invention;

FIG. 2 is a front view thereof;

FIG. 3 is a rear view thereof;

FIG. 4 is a top view thereof;

FIG. 5 is a bottom view thereof;

FIG. 6 is a first side view thereof;

FIG. 7 is a second side view thereof;

FIG. 8 is a top perspective view thereof shown in a first stage of an environmental use;

FIG. 9 is a top perspective view thereof shown in a second stage of an environmental use;

FIG. 10 is a top perspective view thereof shown in a third stage of an environmental use; and,

FIG. 11 is a top perspective view thereof shown in a fourth stage of an environmental use.

The broken lines shown represent unclaimed subject matter and form no part of the claimed design.
